AUGUST R. SCHOENKY, OF SOMERVILLE, MASSACHUSETTS, ASSIGNOR TO REECE SHOE MACHINERY COMPANY, OF BOSTON, MASSACHUSETTS, A CORPORATION OF MAINE.

STOPPING AND STARTING MECHANISM.

1,352,226.

Specification of Letters Patent.

Patented Sept. 7, 1920.

Application filed March 22, 1919. Serial No. 284,451.

To all whom it may concern:

Be it known that I, AUGUST R. SCHOENKY, a citizen of the United States, residing at Somerville, in the county of Middlesex and State of Massachusetts, have invented certain new and useful Improvements in Stopping and Starting Mechanism, of which the following is a specification, reference being had therein to the accompanying drawing.

This invention is a novel stopping and starting mechanism, for example, for power driven sewing machines, and more particularly the invention is a combination of such a machine having certain characteristics, with a stop motion having certain coöperating characteristics.

As a suitable example I may refer to machines for stitching shoe uppers to sole lips, this well known class of machines operating usually to produce a chain stitch, and embodying a hooked, curved needle and co-operating stitching instruments driven from the main or operating shaft. Moreover, the particular design or embodiment of the present invention which will be herein described is best adapted for use on such a machine not having excessive momentum, but on the contrary relatively light running and easily brought from full operating speed to a stop. I may recite as a typical instance of such a machine for stitching shoe uppers to sole lips the prior patent of Zaleski and Schoenky No. 1,288,866, patented December 17, 1918, the smooth and light running qualities of which are secured by the employment of cranks, links and levers by which the rotation of the operating shaft is communicated to the several stitching instruments; and the present invention is shown as applied to a crank, link and lever driven machine for stitching shoe uppers to sole lips constructed substantially on the principles of said patent.

The main object, therefore, of the present invention is to provide a practical, convenient and efficient stop motion adapted to the purposes recited. A peculiarity of machines for stitching shoe uppers to sole lips employing a curved, hooked needle is that in the ordinary cycle of actions in producing each stitch the needle stands substantially within and projecting through the work for one stitch at the point of time in which the preceding stitch is completely formed and taken up, so that, if the machine be stopped

at this point of the cycle, the work is held by the needle and incapable of easy removal from the machine; whereas if the machine be stopped at a later point in the cycle, namely, after the needle has withdrawn from engagement with the work, the thread continues to remain engaged with the needle, and again stands in the way of easy removal of the shoe from the machine. Various schemes have been suggested for automatic prevention of either of the described objectionable conditions upon the stoppage of the machine, but to the present day the plan most commonly practised in the art is the stoppage of the machine without stop motion namely, by placing the hand on the hand wheel of the operating shaft until the forward rotation ceases, but continuing the rotation by hand until the shaft arrives at the position wherein the stitch cycle will be completed, with the needle engaged in the work, followed by a sufficient reversal by hand, judged by the experience and observation of the operator, to cause the retraction of the needle and the freeing of the work for its removal. This mode of stoppage possessed various disadvantages, of which the most pertinent are the necessity of the operator taking his concentrated attention from the stitching in order to give it to the stopping and reversing actions described, and further the necessity of his removing one hand from the work, which theretofore he has effectively guided by the use of both hands.

A particular object of this invention, therefore, is to afford a stop motion which will overcome the recited objections and permit the operator to concentrate his attention on the manipulation of the shoe and the formation of the stitches until the machine is stopped, and will automatically bring about the stoppage of the forward rotation of the shaft at the proper point at the end of the stitch cycle, with the needle engaged in the work, yet will permit subsequently and facilitate the necessary further motion or reversal of the shaft to retract the needle and free the work for its removal.

A further object is to afford a stop motion which will accomplish the purposes just mentioned, and additionally will afford a machine so equipped that it may be stopped more than once or repeatedly, and restarted again during the stitching of a single shoe,

and without incurring the reversing action mentioned until time for the desired retraction of the work upon the completion of the same.

5 Other and more particular objects and advantages of the present improvement will be explained in the hereinafter following description of one form of design or embodiment of the invention, as will be apparent to 10 those skilled in the art.

To the attainment of the objects and advantages referred to, the present invention consists in the novel machine, mechanisms, combinations, arrangements, devices and 15 other features herein described or illustrated.

In the accompanying drawings forming a part hereof, Figure 1 is a front elevation of a stitching machine of the class mentioned, including the stopping and starting mechanism at the left end of the operating shaft.

Fig. 2 is a right elevation, partly in section, of the guard disk 38 shown in Fig. 1.

25 Fig. 3 is a right elevation, partly in section, of the non-rotating clutch member 26 shown in Fig. 1.

30 Fig. 4 is a partial left elevation of the stitching mechanism with the frame broken away, the main shaft in section and many of the parts other than the needle connections omitted.

The main or operating shaft 53 of the machine is shown as extending from the 35 driving connections and starting and stopping mechanism at the left to the stitching mechanism at the right, the shaft being broken away to indicate the omission of numerous parts not essential to the explanation of the present improvement. One of 40 the bearings for the shaft 53 is the standard 54, and at the extreme left the shaft carries a wheel 55, which serves as a hand wheel for performing any reversing or other 45 desirable manipulation by hand.

The complete details of the stitching mechanism are unnecessary to describe in the present application, and reference may be made to the before mentioned Patent 50 1,288,366, or to copending application Serial No. 255,536, filed September 24, 1918, by the same inventors as the patentees of said patent. I have, however, shown certain of the stitching mechanism which I will now refer 55 to. The shoe S is shown in the position in which it is held by the operator during the progress of the stitching. The shoe is held against a support or guide A, is fed toward the left in Fig. 1 by suitable feeding means 60 not shown, while the needle and co-operating stitching instruments perform the stitching.

The main shaft 53 and all the other parts in all the figures are shown in the position which they occupy at the end of a stitch 65 cycle, and the needle C, as before explained,

is at this stage engaged in the work, as indicated.

The needle C is a curved needle having a hook or barb at its forward end, and is fitted for oscillating movement by being carried upon a needle block c, which swings about a stud or pivot c'. In its advancing stroke the needle penetrates first the welt, then the upper, and then the insole of the shoe, and returns during each stitch, the 75 thread being co-operatively manipulated to produce a continuous line of chain stitching.

The actuating connections for oscillating the needle may be as follows. The main shaft 53 is shown as provided with a crank 70 57, which is illustrated in its lowest position.

Extending forwardly and downwardly from the crank 57 is a short pitman or link 62.

The free end of the pitman 62 may be guided as follows. Pivoted on a longitudinal axle 85 f' forward and slightly higher than the main shaft is an arm 69, which extends downwardly and rearwardly, and is pivoted

to the free end of pitman 62, thus controlling its movement during the rotation of the 90 crank. From the stud connecting the pitman and the arm extends downwardly and rearwardly a short link 70, which serves as a connection to a long oscillating lever 73.

The lever 73 has its hub 72 mounted on an 95 axle considerably to the rear of the main shaft, and the lever 73 extends from this axle forwardly and downwardly beneath the main shaft to where at its forward end it is connected by a link 80 to the needle block 100

c. The needle block stands to the rear of its own pivot stud c', and the link 80 extends diagonally therefrom downwardly and rearwardly to the free end of the aforesaid long lever 73.

105 By these connections the curved hooked needle, which is attached to the needle block in a position concentric with the center of oscillation, operates to advance in an arc and penetrate the work, as before described, and before retracting, to receive a loop of the thread, then drawing the thread through the work, and on the succeeding forward stroke occupying such loop and penetrating the work at a new point. When any stitch has 110 been completed, and the needle stands forwardly in the position shown in Fig. 1, it will have been engaged by a new thread loop. If now the forward rotation continues, the thread will be drawn through the 115 work to form, or as if to form, a new stitch. By the present invention the machine will be stopped with the parts in the position shown, and the stopping connections will be such that the operator is at this time able to 120 produce a reversal of a suitable extent, which will first undo the loop on the needle barb, and then withdraw the needle, leaving the work 125 perfectly free to be extracted from the machine.

Coming now to the stopping and starting mechanism hereof, the principle of this is that at the end of the seam or at other suitable time, either automatically controlled or 5 preferably under control of the operator, the main shaft is brought promptly to a stop in its forward rotation and at the point in the stitch cycle, as shown, in which the stitch is completed and the needle stands in 10 the work. Preferably frictional stoppage is employed which may give a sufficiently accurate final stoppage point, in view of the light running qualities and low momentum of the machine, but preferably also the 15 frictional stoppage is supplemented by an impact means to insure the proper final position of the shaft.

One characteristic, therefore, of the present stop motion is that it brings the shaft to 20 rest in a position with the needle engaged in the work, this being the end of the stitch cycle, and as will be more fully explained. Another characteristic of the stop motion is its construction to readily permit the operator 25 through the hand wheel 55 or otherwise to reverse the shaft, thereby disengaging the needle both from the thread and from the work, and attaining one of the objects originally recited. A further characteristic 30 is that, when the stop motion has brought the shaft to rest with the needle in the work, as described, the operator at his election may either reverse the shaft for the removal of the work, or restart the shaft for 35 the continuance of stitching. This latter characteristic is of substantial value in such a machine, because permitting the operator to stitch around the sharp toes or other difficult parts of shoe by short stretches 40 of stitches, so that he may properly guide, turn and inspect the work between stitches during this delicate operation.

In none of the prior attempts to afford 45 automatic stoppage to a machine of the kind described, of which I am aware, has it been possible to exercise any choice or control such as described, or to bring about a restarting and continued stitching after let-up of the needle and stoppage.

Coming to the details of structure and design of the illustrative embodiment of the invention, the shaft 53 is shown as extended considerably to the left beyond the standard or bearing 54, and with the hand wheel 55 at the left extremity. As a source of power I show a belt 19 running on a pulley 20, the pulley being mounted loosely on the shaft 53, and provided with a conical clutch recess 21 at its right face. Keyed upon the 50 shaft 53 to the right of the belt or power pulley is a double acting shifting clutch member 22. This has at its left end a cone 23, adapted to engage in the recess 21 of the power pulley. By this engagement the

stitching machine can be clutched to the 65 power pulley and driven.

The clutch member 22 at its right hand end has a second friction cone 24. This is in the nature of a braking or retarding member, and engages in a conical recess 25 70 in a non-rotating clutch or brake member 26, which surrounds the main shaft 53 and is suitably connected to the bearing standard 54, that is, to the left or enlarged head or end 54^a thereof.

The clutch member 22 requires to be shifted to left or right for driving or stopping the machine, and for this purpose is provided with a peripheral groove 27, engaged by the opposite pins 28 of a forked 80 clutch member 29, connected by a pivot 30 to a fixed bracket 31. The shift lever 29 has an upward extension 32, which is pulled rightward by a spring 33, so as to cause the clutch member 22 to normally engage with 85 the non-rotating complementary clutch or brake member 26, thus bringing and holding the main shaft at rest. The pull of the spring 33 determines the braking force, and to enable this to be adjusted there is shown 90 a screw thread adjusting device 33^a, by which the spring is connected to a fixed part or bracket extending from the bearing standard 54.

For shifting the clutch to cause the starting of the shaft into rotation the lever 29 is provided with a rightward extension 34, and this is connected by a link 35 with a reversing lever 36, centrally pivoted and having a pedal rod 37^a extending downwardly 100 to a pedal 37. When the operative depresses the pedal 37, the clutch lever 29 and member 22 are thrown leftward, causing the cone 23 to engage the recess 21 of the power pulley 20, thus bringing about full speed drive. 105 When the pedal is released, the spring 33 comes into action to force the clutch member 22 to the right, causing it to engage the friction brake member 26, which quickly brings the shaft to rest. Owing to the slight 110 rotary momentum of the machine, due to the absence of cams and other heavy rotary parts, it is practical to bring the shaft to rest by friction, as described, within approximately a quarter rotation, and giving fairly 115 accurate final position.

Inasmuch as the mere application of friction as described might cause the shaft to stop at any indefinite point, whereas it is desired to stop the parts at the end of a 120 stitch cycle, means are provided to prevent the application of the friction, that is, the engagement of the co-acting members 24 and 26 until a predetermined extent, for example, a quarter rotation, prior to the desired final stopping point. A suitable means for this purpose consists of a guard or disk 38, pinned to the shaft 53, so as to rotate

4
with it, and having a groove 39 at its left face, the same coöperating with a guard pin 40, shown as mounted to slide to right and left in the bearing standard 54. For a reason to be explained, the righthand end of the guard pin is also capable of swinging up and down, and the standard is recessed as shown, to admit this motion, while a spring 40^a is provided tending to thrust the guard pin to its upper or normal position, which is shown in dotted lines in Fig. 1.

The guard pin 40 effects control over the clutch, and to bring this about is shown as connected by a link 41 with the clutch lever 29. The right extremity of the guard pin is normally to the left of the guard disk 38, the latter preventing it from moving rightward to the position shown in full lines. By this construction the clutch lever 29 cannot move toward the right to throw in the friction brake members until the guard disk 38 permits the pin 40 to move rightward to the position shown. The operation of these parts is that about a quarter rotation before the final stopping point, the pin 40, which is caused to tend toward the right by the spring 33, when the pedal 37 has been let up, is enabled to drop into the groove 39 of the guard disk. For this purpose the groove 39 is shown as about a quarter revolution in extent, and it is preferably slightly eccentric, so that the pin 40 can only drop into the initial or first end 39^a of the groove. At this stage the disk and groove will be in the position shown in dotted lines in Fig. 2, while the pin will be at its elevated position slightly higher than the full line position shown in Fig. 2. As soon as the pin drops into the groove, the clutch shifts and the friction takes effect for a quarter rotation up to the point of final stoppage, which is that shown in full lines in Figs. 1 and 2. A slight variation would be of no consequence. While friction is never entirely accurate or constant in its operation, it may in this case be so adjusted as to preclude the possibility of premature stoppage, and the described mechanism may be supplemented by providing a slight enlargement at the terminal end of the groove 39, and placing therein a suitable spring buffer device 42, to take up the final impact. The rebound would be negligible, and would be instantly taken up, because the stopping friction remains in effect.

The mechanism thus far described serves practically to bring the machine to a stop at the end of a stitch cycle and with the needle engaged in the work. The illustrated stop motion is so constructed as to now permit and facilitate the ready backing up of the shaft to the proper extent, namely, about a quarter revolution, for the purpose of retracting the needle to disengage it from the work, thus freeing the work for ready

removal from the machine. This object is attained in the illustrated machine by constructing and combining the non-rotating clutch or friction member 26, so that it may receive a slight reverse rotation, that is to say, about a quarter rotation, depending on the extent of reverse needed to bring the empty needle back out of the work.

To this end the friction brake member 26 is shown as loosely surrounding the shaft 53, but limited in its movement by means of a fixed pin 43, secured in the bearing standard 54, and projecting leftward into a quadrantal groove or recess 44 in the member 26, as more fully shown in the righthand view, Fig. 3. A helical spring 45 is inserted within the friction member 26, and surrounding the shaft 53, and so arranged as to tend to rotate the member 26 forwardly, that is, in the direction of the long arrow, Figs. 1 and 3, so as to hold it normally in the position shown in Fig. 3 against the stop pin 43. The spring 45 has one end 46 projecting into the bearing standard extension 54^a, and its other end 47 into the brake member 26. 90

By this arrangement the friction member 46 serves effectively as a brake to effect the stoppage of the forward rotation of the shaft, but additionally permits the shaft after such stoppage at the end of a stitch cycle to be reversely rotated, that is, in the direction of the short arrows, and to the extent of the length of the groove 44, that is, about a quadrant in this case, despite the frictional grip of the member 26 on the clutch member and shaft. The spring 45, while effective for normally maintaining the member 26 in its proper position, offers but negligible resistance to the described reverse rotation. The engagement of the guard pin 40 with disk 38 is of no hindrance to the reverse rotation, because the quadrantal slot 39 freely permits the parts to be shifted back from the full line to the dotted line position shown in Fig. 2. 105

Another concrete advantage in the described structure is that, owing to the groove 44 having a predetermined length, depending on the extent of reverse rotation required to withdraw the needle effectively from the work, this gives the operator a proper indication as to how far he has to reverse the shaft, thus taking his attention and observation entirely away from this part of the operation. When the end of a seam has been reached, or for other reason it is desired to stop the stitching, the operator simply releases the treadle 37, and thereupon, as soon as the guard pin 40 drops into the groove 39 of the guard disk, the friction takes effect and the shaft comes to rest in the position shown. The operator keeps both hands on the shoe, guiding it, up to the last moment. If it is now desired to extract the shoe from the machine, 115

the operative merely reaches one hand to the hand pulley 55, turning it toward him as far as permitted by the engagement of the pin 43 in the groove 44, or by the engagement 5 of the pin 40 in the groove 39. At the end of this motion the needle is retracted and the work is extractable. The spring 45 will be insufficiently strong to cause the forward rotation of the shaft, and therefore 10 when the shaft has been reversed, as described, the friction will hold it in that position, and the operator is not compelled to maintain his hand on the reversed wheel 55 during or after the extraction of the shoe. 15 After the machine has been so stopped and reversed and the work extracted, the process of resuming stitching on another shoe is simply to insert the shoe in place and press the pedal 37. This simultaneously 20 throws the clutch member 22 across to the power pulley, and withdraws the guard pin 40 from the guard disk. The spring 45 automatically and at once rotates the friction member 26 forwardly a quarter turn to its 25 normal position shown.

When the shaft has been stopped, but before the reversal and extraction of the work, the operator may restart the stitching on the same shoe, which affords an advantage in 30 certain classes of work, for example, in the stitching of the toes of pointed shoes, in which it is sometimes desirable to proceed by making one or two or more stitches at a time, followed by stoppage and resumption, enabling the operator to more deliberately swing the shoe around to accord with the progress of the stitching. This function may be attained by merely depressing and immediately releasing the pedal, which will 35 start up the machine and cause its prompt stoppage after only a single stitch, if desired. Such stoppage is always at a point with the needle in the work, so that the needle forms a pivot about which the work 40 may be swung in turning it for further stitching. The stoppage of the forward rotation is automatic, but the described reversing action, being non-automatic, may be postponed until the final completion of the 45 stitching of the shoe, at which time, by reversing the hand wheel as described, the completed shoe may be readily removed and a new one inserted.

It will thus be seen that I have thus described a stopping and starting mechanism embodying the principles and attaining the objects and advantages recited, and also a combination of such mechanism with a stitching machine of the particular class referred to, wherein each stitch cycle is completed at a time when the curved hooked needle is engaged within the work. Since many matters of design, arrangement, form, combination, details and other features may 55 be variously modified without departing

from the principles involved, no limitation to such features is intended except in so far as referred to in the appended claims.

What is claimed is:

1. In a machine for stitching shoe uppers 70 to sole lips, chain stitching mechanism comprising a curved hooked needle operating so that the needle stands in the work at the completion of each stitch, a frictional stopping means controlled to cause stoppage 75 with the needle in the work, and a slip connection associated with said stopping means such as to permit reversal sufficient to extract the needle.

2. In a machine for stitching shoe uppers 80 to sole lips, chain stitching mechanism comprising a curved hooked needle operating so that the needle stands in the work at the completion of each stitch, an operating shaft actuating said stitching mechanism, drive 85 means for rotating said shaft, a control lever or pedal, connections controlled by said lever for applying force to stop the shaft, means associated with said stopping connections to insure the shaft stopping at the completion of a stitch with the needle engaged in the work, and a slotted or recessed part associated with said stopping connections to permit reversal of the stopped shaft to an extent to extract the needle; whereby when 95 the machine is stopped the operator at will may restart it or reverse the shaft to extract the needle and release the work.

3. In a stitching machine, an operating shaft, stitching mechanism actuated thereby, 100 drive means therefor, and a stopping mechanism comprising opposed co-operating friction members, one turning with the shaft, the other non-rotatable but fitted to turn reversely for a fraction of a rotation, where- 105 by on stoppage the shaft may be manually reversed for such fraction of a rotation.

4. A power driven shoe sewing machine of the class known as welt-and-turn stitching machine, adapted for stitching the shoe 110 upper to the lip of its sole, and comprising in combination, a chain stitching mechanism for actuating the usual curved hooked needle, operating so that the completion of each stitch occurs at a time when the hooked 115 needle is engaged in the leather preparatory to drawing a thread loop through the leather for the succeeding stitch, and a stopping mechanism operating to stop the machine and leave it at rest at the point of completion of a stitch with the needle engaged in the leather, such stop motion being adapted to permit at will a sufficient reverse rotation of the machine to extract from the leather the needle in threadless condition, 120 thus releasing the shoe and thread from the needle and facilitating ready removal of the stitched shoe from the machine.

5. A power driven shoe sewing machine of the class known as welt-and-turn stitch- 130

ing machine, adapted for stitching the shoe upper to the lip of its sole, and comprising in combination, a chain stitching mechanism, for actuating the usual curved hooked needle, operating so that the completion of each stitch occurs at a time when the hooked needle is engaged in the leather preparatory to drawing a thread loop through the leather for the succeeding stitch, and a stopping mechanism operating to stop the machine and leave it at rest at the point of completion of a stitch with the needle engaged in the leather, such stop motion having a braking or stopping member acting to apply stopping force to the machine, the said member being capable of being rotated, after the machine has come to rest, in a reverse direction, along with the parts which have been stopped by it, sufficiently to effect the extraction from the leather of the needle in threadless condition, thus releasing the shoe and thread from the needle and facilitating ready removal of the stitched shoe from the machine.

6. A power driven shoe sewing machine of the class known as welt-and-turn stitching machine, adapted for stitching the shoe upper to the lip of its sole, and comprising in combination, a chain stitching mechanism for actuating the usual curved hooked needle, operating so that the completion of each stitch occurs at a time when the hooked needle is engaged in the leather preparatory to drawing a thread loop through the leather

for the succeeding stitch, and a stopping mechanism operating to stop the machine and leave it at rest at the point of completion of a stitch with the needle engaged in the leather, such stop motion being adapted to permit at will a reverse rotation of the machine, and a limiting means acting to prevent reverse rotation of the stopped parts beyond a predetermined extent sufficient to extract the needle from the leather.

7. A power driven shoe sewing machine of the class known as welt-and-turn stitching machine, adapted for stitching the shoe upper to the lip of its sole, and comprising in combination, a chain stitching mechanism for actuating the usual curved hooked needle, operating so that the completion of each stitch occurs at a time when the hooked needle is engaged in the leather preparatory to drawing a thread loop through the leather for the succeeding stitch, and a stopping mechanism operating to stop the machine and leave it at rest at the point of completion of a stitch with the needle engaged in the leather, such stop motion having a frictional stopping member manually rotatable to a limited extent, after the machine has come to rest, and in a reverse direction, along with the parts stopped by it, sufficiently to extract the needle from the leather.

In testimony whereof, I have affixed my signature hereto.

AUGUST R. SCHOENKY.
